(74) Attorney, Agent, or Firm — Kimberly-Clark Worldwide, Inc.

(57) **CLAIM**

The ornamental design for a rolled tissue product, as shown and described.

DESCRIPTION

The sole FIGURE is a perspective view of a rolled tissue product comprising our new design.

The broken lines and areas within them depict portions of the rolled tissue product that form no part of the claimed design.

1 Claim, 1 Drawing Sheet# US D831,979 S
